UNITED STATES PATENT OFFICE

2,443,111

LUG STRAP

William McKinley, Brantford, Ontario, Canada

Application May 24, 1946, Serial No. 671,963

7 Claims. (Cl. 139—153)

1

This invention relates to improvements in a lug strap and appertains particularly to such a device for transmitting the movement of the connecting rod or like operating member to the shuttle-throwing sweep stick in a conventional power loom.

An object of the invention is to provide an improved lug strap mounted on the free end of a driven reciprocating member for operating the sweep stick having a novel stick-engaging cushion heel.

Another object of the invention is to provide an improved sweep stick lug strap having an easily replaceable, laminated leather heel or cushion block.

Another object of the invention is to provide a lug strap for the sweep stick of a power loom having a cushion heel formed of laminated leather replaceably secured between spaced side plates and held against circumferential displacement by the unique inter-engaging formations of the cushion block and side plates.

A still further object of the invention is to provide a lug strap for the sweep stick of a power loom of the nature and for the purposes described that is characterized by structural simplicity, operative efficiency, durability, and ease of installation and replacement of parts and being capable of manufacture at reasonable cost is thereby rendered commercially desirable.

To the accomplishment of these and related objects as shall become apparent as the description proceeds, the invention resides in the construction, combination and arrangement of parts as shall be hereinafter more fully described, illustrated in the accompanying drawings, and pointed out in the claims hereunto appended.

The invention will be best understood and can be more clearly described when reference is had to the drawings forming a part of this disclosure wherein like characters indicate like parts throughout the several views.

In the drawings:

Figure 1 is a perspective view of the improved lug strap; and

Figures 2 and 3 are elevations of the heel end and side respectively of said lug strap.

In the conventional power loom, each reciprocation of the connecting rod imparts quite a jar to the sweep stick or picker stick or staff as the hinged, shuttle-throwing arm is variously called. For this reason some sort of cushion, pad or buffer in the heel or sweep stick engaging end of the lug strap is desirable. In some areas it is common practice to use a cotton packing but I

2

have found that a large-sized heel of laminated leather secured in the end of the lug strap with a substantial area facing the outside of the picker or sweep stick possesses many and great advantages being more durable than the cotton, can occur in greater depth because of the inherent qualities of the substance, especially in laminated form, can be secured by a single fastening bolt and held against rotative displacement thereon by the structural formation or configuration of the laminated leather cushion block and the lug's side plates, all of which makes for easy and rapid replacement and relatively cheap manufacture.

The preferred embodiment of the lug strap shown in the drawings, being characteristic of the instant invention comprises a pair of side plates 5 each formed of an elongated strip of steel or other suitable metal, rounded as at 6 at one end and provided with a longitudinally spaced pair of transverse perforations 7 on the longitudinal median. By means of these perforations the plates 5 are secured by transverse fastening bolts and nuts to the free or outer end of the connecting rod or other driving mechanism of the loom, which being common practice obviates the need to show either the fastening bolts or loom's connecting rod.

Near the opposite end, each side plate 5 has a transverse perforation 8 on its longitudinal median and the end 9 of the strap bent at a right angle with the center portion 10, representing approximately one-third of the height interrupted or cut away for the entire width thereof so that the inbent angular end appears as a pair of vertically spaced upper and lower fingers 11 and 12.

A heel cushion block 14 consisting of laminated leather with the several sheets thereof standing vertically is disposed between the pair of elongated, laterally spaced pair of parallel side plates 5, and abutting the fingers 11 and 12 of the inturned end flanges 9 thereof, extends inwards therefrom beyond the registering perforations 8. This laminated heel block 14 is of the same height as the side plates 5, terminating flush with upper and lower edges thereof and of approximately the same width as the connecting rod of the loom engaged by the opposite end of the assembled lug strap. The overlying flanges 9 on the ends of the side plates each extend but about one-third of the way across the end of the heel block 14 leaving approximately the centre one-third open.

A transversely disposed tongue 15 extends horizontally from the end of the block 14 midway of the height across the entire width thereof and

lies between the vertically separated fingers 11 and 12 of each side plate 5, projecting even beyond the flanged ends 9.

This laminated leather block is secured in place between the side plates 5 by a transverse bolt 16 passing through the perforations 8 and the laminated leather and is removably held by a confining washer 17 and threaded nut 18. The bolt passes through the side and block midway of their height but the latter preferably extends beyond the bolt substantially more than one-half its entire length to allow for wear.

In use, this laminated leather heel cushion will be found to engage the sweep stick most efficiently, occasioning less jar, affording longer useful life, and being so easily and quickly changed. The projecting tongue lying between the vertically separated fingers on the end flanges that share with the transverse bolt and compressed side plates in absorbing the blow on the cushion, effectively prevents the heel from turning on the single securing bolt.

From the foregoing description taken in connection with the accompanying drawings, it will be manifest that a lug strap is provided that will fulfil all the necessary requirements of such a device but as many changes could be made in the above description and many apparently widely different embodiments of the invention may be constructed within the scope of the appended claims, without departing from the spirit or scope thereof, it is intended that all matters contained in the said accompanying specification and drawings shall be interpreted as illustrative and not in a limitative or restrictive sense.

Having thus described the invention, what I claim as new and desire to secure by Letters Patent is:

1. A lug strap for the sweep stick of a power loom comprising a pair of spaced elongated side plates each having a vertically separated pair of fingers bent inwards at one end and a laminated leather cushion heel secured between said side plates and abutting said inturned fingers and projecting between said vertically separated fingers.

2. A lug strap for the sweep stick of a power loom comprising a pair of spaced elongated side plates each having a vertically separated pair of fingers bent inwards at one end and a laminated leather cushion heel secured between said side plates and abutting said inturned fingers, said heel having a projecting horizontal tongue extending between the vertically separated inturned fingers on an end of each of said side plates.

3. A lug strap for the sweep stick of a power loom comprising a pair of spaced elongated side plates each having a vertically separated pair of fingers bent inwards at one end and a laminated leather cushion heel secured between said side plates and abutting said inturned fingers, said heel having a horizontal tongue extended from an end thereof across its full width and lying between the vertically separated inturned fingers of said respective plates.

4. For a power loom having a reciprocating connecting rod or like driving member and a sweep stick, a lug strap for attachment to the connecting rod comprising a pair of elongated side plates attached by one end to opposite sides

of said rod, a resilient cushion block of laminated sheets of leather tightly compressed between the free outer ends of said plates intermittently engaging said sweep stick, a removable securing bolt extended transversely through said side plates and the several sheets of the intermediate cushion block, a nut on said bolt tightly compressing said laminated block and supplementary displacement preventing means formed on said block and engaging said side plates.

5. For a power loom having a reciprocating connecting rod or like driving member and a sweep stick, a lug strap for attachment to the connecting rod comprising a pair of elongated side plates attached by one end to opposite sides of said rod, a cushion block of laminated leather between the outer ends of said plates intermittently engaging said sweep stick, removable fastening means extended transversely through said side plates and intermediate cushion block tightly compressing the same and displacement preventing means protruding from said block and accommodated by side plates.

6. For a power loom having a reciprocating connecting rod or like driving member and a sweep stick, a lug strap for attachment to the connecting rod comprising a pair of elongated side plates attached by one end to opposite sides of said rod, a laminated leather heel whose sheets stand vertically disposed between the side plates at a distance beyond the end of said rod and engageable with said sweep stick, a removable fastening means extended transversely through said side plates and all the sheets of the intermediate laminated leather heel and inter-engaging means on said laminated leather heel and said side plates, preventing relative rotative displacement of said heel and side plates.

7. For a power loom having reciprocating connecting rod or like driving member and a sweep stick, a lug strap for attachment to the connecting rod comprising a pair of elongated side plates attached by one end to opposite sides of said rod, centrally interrupted inturned flanges at the free end of said plates occurring as vertically spaced fingers, a cushioning heel of laminated leather disposed between the side plates, abutting said inturned flanges, said cushioning heel being of a thickness to hold the vertically spaced fingers of said inturned flanges in confronting but transversely spaced relation, a horizontal tongue extended from an end of said heel across its full width and lying between the vertically separated fingers of said flanges and a compressing removable fastener extended horizontally through said plates and laminated heel approximately centrally of the latter.
